UNITED STATES PATENT OFFICE.

SARAH A. FLETCHER, OF CHICAGO, ILLINOIS.

SAD-IRON STAND.

1,140,146.

Specification of Letters Patent.

Patented May 18, 1915.

Application filed June 25, 1914. Serial No. 847,219.

To all whom it may concern:

Be it known that I, SARAH A. FLETCHER, a citizen of the United States, residing at Chicago, in the county of Cook and State 5 of Illinois, have invented certain new and useful Improvements in Sad-Iron Stands, of which the following is a specification.

This invention relates to improvements in devices for supporting sad-irons over a gas 10 burner or other heater, and its object is to provide a stand which is constructed to support irons of different sizes, and which concentrates the heat against the bottom thereof so that the iron may be quickly 15 heated.

In order that the invention may be better understood, reference is had to the accompanying drawing, in which—

Figure 1 is a plan view of the stand, and 20 Fig. 2 is a cross-section on the line 2—2 of Fig. 1.

Referring specifically to the drawing, the stand is a dome-shaped member 8 open at the bottom and having a top opening 9 in 25 which the sad-iron to be heated is adapted to seat. The stand may be, and preferably is, a casting. The top opening conforms to the outline of the base of an ordinary sad-iron.

The stand is designed to be placed over a 30 gas burner or other heating medium, and when thus placed, with the iron supported in the opening 9, the heat from the burner is concentrated against and spread over the bottom of the iron, and it is quickly heated. In removing the iron, there is no danger 35 of burning the hand over the gas flame, as the stand covers the latter and the iron seats in and entirely closes the opening 9.

The opening 9 has a step or shoulder 10, and said step or shoulder does not extend 40 entirely around the opening, but is only on one side thereof, and on the opposite side of the opening, the top of the stand has an out-standing shelf 11, the top of which is flush with the shoulder 10.

The purpose of the shelf 11 is to provide 45 a temporary support for an iron while another iron is in place over the opening 9. The handle of the iron resting on the shelf will be removed and attached to the heated 50 iron seating over the opening 9, whereupon the heated iron may be removed and the cold iron resting on the shelf pushed over to the opening to be heated. The shelf therefore enables a cold iron to be easily 55 and quickly exchanged for a hot one. The shoulder 10 serves as an abutment to keep the iron from sliding over too far when it is pushed in place over the opening.

I claim:

A sad-iron stand comprising a dome-shaped member open at its bottom and closed 60 at its side, and having a top opening, and a shelf projecting from one side of the top opening, the other side of said opening being shouldered said shoulder rising above the plane of the top of the shelf and the bottom of the shoulder being level with said shelf top.

In testimony whereof I affix my signature 70 in presence of two witnesses.

SARAH A. FLETCHER.
